UNITED STATES PATENT OFFICE.

MORRIS B. BREWSTER, OF COLUMBUS, OHIO.

AUTOMATIC STOKER.

No. 880,623.

Specification of Letters Patent.

Patented March 3, 1908.

Application filed June 12, 1907. Serial No. 378,592.

To all whom it may concern:

Be it known that I, MORRIS B. BREWSTER, a citizen of the United States, residing at Columbus, in the county of Franklin and 5 State of Ohio, have invented certain new and useful Improvements in Automatic Stokers, of which the following is a specification.

My invention relates to new and useful improvements in mechanical stokers.

10 The object of the invention is to provide a combined fuel feeding and grate rocking mechanism of a superior form.

Another feature is to provide in combination with the rocking grate mechanism, 15 means for distributing the fuel in the combustion chamber, together with means for keeping said distributing means "cool" and also assist in the distribution.

Another feature resides in a novel feeding 20 mechanism carried by both the locomotive and tender and involving a novel joint and other peculiar mechanism.

Finally the object of the invention is to 25 provide a device of the character described 5 that will be strong, durable and efficient and one in which the several parts will not be liable to get out of working order.

With the above and other objects in view, 30 the invention has relation to the production 35 of mechanical stokers, a practical embodiment of which is described in the specification and illustrated in the accompanying drawings, wherein:

Figure 1 is a horizontal, sectional view 35 showing a portion of the fire box and frame of a locomotive with my improved stoker applied thereto, Fig. 2 is a partial longitudinal vertical sectional view of a locomotive and tender and the stoker, Fig. 3 is a vertical section view of the connecting screw and its casing taken on the line A—A of Fig. 2, Fig. 4 is a transverse vertical section taken on the line B—B of Fig. 2 and looking in the direction of the arrows, Fig. 5 is an elevation of 40 the fire box, showing the fire door and the distributing steam connection; Fig. 6 is a longitudinal vertical section of the tender and the stoker, Fig. 7 is a transverse vertical section of the same, Fig. 8 is a plan view of 45 the tender and stoker, and Fig. 9 is an enlarged detail of the tender screw and its trough.

In the drawings the numeral 1, designates 50 the locomotive fire box or combustion chamber, and 2 the back sheets. At the lower end of the combustion chamber a central longi-

tudinal grate bar 3 is arranged terminating at its rear end in an enlargement 4 as shown in Fig. 1. Opposite this bar side bars 5 are suitably mounted. Between the bars suitable grates 7 are pivotally mounted. These grates are arranged in four sets lettered A, B, C and D and connected with suitable mechanism hereinafter described, so that each set is operated successively and one at a time. The grates are so mounted as to swing upward and forward, acting to work the coal toward the front end of the combustion chamber.

At the forward end of the combustion 70 chamber centrally pivoted dump grates A' and D' are arranged and connected to operate in unison with the grates forming the A and D sets respectively. At the feeding end of the combustion chamber stationary 75 grates 8 are mounted in each corner, while short grates A², B², C² and D² are pivoted at right angles to the other grates and arranged to swing upward and toward the sides of the combustion chamber, being connected to operate in unison with the sets bearing the same respective letter. It is obvious that fuel delivered to the combustion chamber will be carried to each side and forward by the grates, and after combustion 85 dumped by the grates A' and D' into the ash-pan. (Not shown.)

In Figs. 6, 7, 8 and 9 I have shown a tender body formed with a hopper 10 terminating in a central longitudinal screw or conveyor trough 11. In this trough a screw 12 is suitably mounted. The trough is covered a considerable portion of its length by plates 14 which keep the weight of the fuel off the screw, so that the forward portion of said 90 fuel is removed first, the plates 14 being successively moved forward or removed as the coal is used up. The trough terminates at its forward end in a bowl 15 which receives the ball end 16, of a connecting trough 100 comprising telescoping sections 17 and 17' said section 17' being formed at its outer end with a ball 18 fitting in the bowl end 19 of a conveyor trough 20 carried by the locomotive. In this way universal joints are provided between the troughs, the connecting trough being made as described in telescoping sections, so that play between the locomotive and tender in all directions is afforded. In the connecting trough a screw 21 is 105 mounted. This screw receives separable squared shafts 22 and 23 which are connected,

one to the screw 12 by a clevis 24, and the other to a screw 25 mounted in the trough 20 by a clevis 26. Thus when the locomotive and its tender are coupled or uncoupled, my improved conveyer may be likewise coupled or uncoupled by means of the clevises 24 and 6, the section formed by squared shafts 22 and 23 and the screw 21 being turned up at one end when disconnected at the other as shown in dotted lines in Fig. 2. The screws 21 and 25 extend under the deck 27 of the locomotive and a hinged cover 28, of the telescope sections 17 and 17'. The trough terminates in a vertical screw casing 29 beneath the combustion chamber, the said casing passing up through the grate bar enlargement 4 and terminating flush with the surface thereof. In this casing a vertical screw 30 is arranged and projects a short distance above the enlargement and the grate line. It will be apparent that motion being imparted to the screws, the fuel will be conveyed forward, up through the casing and scattered in the combustion chamber by the screw 30, the grates operating to distribute and carry the fuel forward, as previously described.

It is obvious that owing to the intense heat the vertical screw 30 would become so hot, being exposed to the fire, as to become soft and useless. To prevent this the center of the screw is hollow and its upper end closed. Steam supplied to the screw is ejected through perforations 31 which not only maintains the temperature of the screw at a low degree of heat but assists in scattering the fuel. The steam is supplied in any suitable manner, as by a pipe 32 (see Fig. 5) having connection with the exhaust of a suitable engine which is used to drive the gearing hereinafter described. This pipe 32 is telescopingly disposed at its end within the lower end 33 of the hollow vertical shaft of the screw 30.

I will now describe the mechanism for imparting motion to the various screws. A drive shaft 35 is supported from the outer sheet 2 in bearings 36, and extends transversely across the locomotive, carrying on its end a miter gear 37 and near this gear a worm 38. This worm meshes with a worm wheel 39 having a clutch side and loosely mounted on a counter shaft 40 lying beneath and suitably supported at right angles to the drive shaft 35. The clutch face of this gear 39 is adapted to be engaged by a clutch member 41 by which the imparting of motion to the counter shaft may be controlled. The counter shaft 41 also carries a spur gear 42 which meshes with a pinion 43, cast on the locomotive screw 25, which imparts motion to the screws 21 and 12 by means of the connections hereinbefore described.

The miter gear 37 on the end of the shaft 35 meshes with a miter gear 44 mounted on the

upper end of a suitably supported inclined shaft 45, which carries near its lower end a worm 46. This worm meshes with a worm wheel 47 mounted on the end of a short transverse shaft 48 supported below the screw 70 casing 29 in a depending arm 49 of said screw casing 29, which arm provides at its lower end a bearing 50 for the lower end of the inclined shaft 45. The short shaft 48 carries on its opposite end a miter gear 51 75 which meshes with a miter gear 52 fixed on the lower portion 33 of the shaft of the vertical screw 30 as shown in Fig. 4.

Intermediate its ends, the inclined shaft 45 carries a worm 53 which meshes with a worm wheel 54 carried on a transverse shaft 55 mounted in bearings between the longitudinal supporting brackets 56 which further support a transverse shaft 57 in parallelism with said shaft 55. The shaft 55 carries a pair of double cams 58 which operate against the vertical levers 59, swingingly mounted on the parallel shaft 57, (as shown clearly in Fig. 2) and actuate the horizontal levers 60, pivotally connected at the upper 90 ends of said levers 59, to rock the sets of grates A, B, C and D as previously described, by means of the individual grate connecting levers 61. The vertical levers 59, in their movement, are arranged to strike and operate bell-crank-levers 62, mounted on short shafts 63 depending from the fire box 1, to similarly actuate the short grates A², B², C² and D² as described, by means of their individual connecting levers 64. 100

Projecting within the fire box 1 at the upper end of the vertical screw 30 I preferably arranged a plurality of distributing nozzles 65 extending from a manifold 66 and adapted to emit an intermittently regulated supply of fluid under pressure to assist in the more perfect distribution of the coal within the fire box 1. The manifold 66 has connection with a valve cylinder 67 by means of a pipe 68, said valve cylinder having a fluid inlet pipe 69 connected thereto and having arranged therein a double headed piston 70 continuously reciprocated to alternately cut-off and open the mouth of the manifold pipe 68, by means of a strap or other eccentric 115 71 mounted either on the drive shaft 35, or on some other suitably rotating element.

Having thus fully described my invention I claim:

1. The combination with a locomotive 120 and its tender having a fuel conveyer provided with a removable section universally jointed therein between the cars, of a fire box having movable grates, means for distributing the fuel from said conveyer to said grates, and mechanism for simultaneously operating said conveyer and grates, substantially as described.

2. The combination with a locomotive 125 and its tender having an extensible remov-

able section universally jointed therein between the cars, of a fire box having movable grates, means for distributing the fuel from said conveyer to said grates, and mechanism for simultaneously operating said conveyer and grates, substantially as described.

3. The combination with a locomotive and its tender having a separable fuel conveyer provided with a removable section universally jointed therein between the cars, of a fire box having movable grates, means for distributing the fuel from said conveyer to said grates, and mechanism for operating said conveyer, said distributing means, and said

15 grates, substantially as described.

4. The combination with a locomotive and its tender having a separable fuel conveyer provided with an extensible removable section universally jointed therein between the cars, of a fire box having movable grates, means for distributing the fuel from said conveyer to said grates, and mechanism for simultaneously operating said conveyer, said distributing means, and said grates, substan-

25 tially as described.

5. The combination in a device of the character described, of a locomotive and its tender and a conveyer for delivering fuel from said tender to said locomotive, and having a removable section, universally jointed therein between the cars, substantially as described.

6. The combination of a device of the character described, of a locomotive and its tender and a conveyer for delivering fuel from said tender to said locomotive, and having an extensible removable section, universally jointed therein between the cars, substantially as described.

7. The combination with a locomotive and its tender having a separable universally jointed fuel conveyer arranged therebetween, of a fire box, a fuel conveyer projecting therein to deliver the fuel and having a perforated tubular member, and means for

forcing a fluid therethrough, substantially as described.

8. In apparatus of the character described, a conveyer for introducing fuel into a combustion chamber, said conveyer being adapted and arranged to elevate said fuel approximately vertically into said chamber and having a hollow perforated shaft, intermittent fluid pressure means for distributing said elevated fuel in said chamber, and means for forcing a fluid through said shaft to cool the same and said conveyer and assist in the distribution of the fuel, substantially as described.

9. In an apparatus of the character described, means for conveying fuel from a tender to a locomotive, a screw conveyer in combination with said conveying means, said screw conveyer being adapted and arranged to elevate said fuel upwardly through the base of the locomotive fire box, and having a hollow perforated shaft, intermittent fluid pressure means for distributing the fuel in said fire box, and means for forcing a fluid through said shaft to cool the same and said screw conveyer and assist in the distribution of the fuel, substantially as described.

10. The combination with a locomotive and its tender having a fuel conveyer arranged to deliver fuel from said tender to said locomotive and having an extensible, removable section universally hinged therein between the cars, means for distributing the fuel from said conveyer to said grates, and mechanism for simultaneously operating said conveyer, said distributing means and said grates, substantially as described.

In testimony whereof I affix my signature in presence of two witnesses.
